CABINET

Frank H. Thompson, Baltimore, Md.

Application July 13, 1934, Serial No. 735,053

3 Claims. (Cl. 312—162)

This invention relates to furniture, and its general object is to provide a cabinet that is primarily designed for use in a bed room and preferably with respect to the sides of a bed or between twin beds, in that the cabinet includes an adjustable platform for disposal over a bed to be used as a writing surface or a table for meals and the like and without fear of the cabinet falling or tipping, due to the fact that it is self-supporting and constructed to stabilize the overhang of the platform when fully extended for use, with articles and the like thereon.

Another object of the invention is to provide a cabinet that can be moved with ease from place to place, and includes drawers and other storage space, as well as illuminating means and space for a radio, with means for controlling the illuminating means and radio from either side of the cabinet, and the latter also includes conveniently arranged outlets for electrical apparatus such as a percolator, toaster, heating pad and the like, with the result it will be seen that the cabinet is extremely useful and convenient for the purpose intended in any room and place desired.

Another object of the invention is to provide a cabinet of the character set forth, that is reasonably simple in construction, inexpensive to manufacture and efficient in use and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a front view of the cabinet which forms the subject matter of the present invention.

Figure 2 is a rear view thereof.

Figure 3 is a vertical sectional view taken through the cabinet.

Figure 4 is a sectional view taken approximately on line 4—4 of Figure 3, looking in the direction of the arrows.

Figure 5 is a sectional view taken approximately on line 5—5 of Figure 3, looking in the direction of the arrows.

Figure 6 is a fragmentary view showing one of the switch and outlet plates.

Referring to the drawing in detail, the reference numeral 1 indicates the base of my cabinet which as shown includes a rectangular portion acting to receive the body of the cabinet and

formed with the sides of the rectangular portion is a forwardly directed substantially V-shaped portion 2 which together with the rectangular portion has secured to the other side thereof, casters 3. However, the base may be of any shape capable of performing its intended function, with any number of casters thereon.

The body of the cabinet includes a rear wall 4, side walls 5, a top 6 and a bottom 7, and the lower portion of the front of the cabinet is closed by a panel 8.

Mounted for vertical movement within the cabinet so as to be adjusted to various heights is a platform including a body portion 9 which has secured to the underside thereof a frame 10 of substantially rectangular formation, and the body portion has secured thereto and depending transversely therefrom what may be termed a shielding member 11 that is engageable with the inner side of the panel 8 as best shown in Figure 3.

The body member is provided with an extension or leaf 12 which is hingedly secured to the forward edge thereof and is held in operative position through the instrumentality of a sliding strip 13 that is mounted for slidable movement in the forward portion of the frame 10.

While other means may be used to hold the platform in its respective adjusted positions I show a latching means which includes a lever 14, the latter being pivotally secured to the underside of the body portion as at 15 and having pivotally secured to the inner end thereof an arm 16. The lever also has pivotally secured thereto intermediate its ends, one end of an arm 17 that is relatively longer than the arm 16 and the arms are arranged so that their outer ends are receivable in any pair of a plurality of superimposed bores 18 that are disposed in the inner surface of the side walls 5, and a coil spring 19 has its end convolutions engageable with the lever and a side of the frame 10 in order to urge and hold the arms 16 and 17 in companion bores.

Arranged in the upper portion of the cabinet and centrally thereof is a compartment 20 which as shown is adapted to receive a loud speaker 21 or of a radio instrument 22, the latter being arranged in the lower portion of the cabinet and preferably supported upon a shelf 23. It is obvious that the loud speaker is electrically connected to the instrument which is controlled by suitable means having control knobs 24 disposed upon opposite sides of the front of the cabinet as best shown in Figure 1. A suitable lamp for reading and the like is secured to the front of the cabinet at the upper end thereof and for distinction

is indicated by the reference numeral 25, while arranged below the compartment 20 is a chamber 26 that has disposed therein illuminating means 27 that acts in the capacity as a night light, due 5 to the fact that the illuminating means which is in the form of an electric lamp extends from the rear wall 4 of the cabinet, so that it is amply shielded by its chamber.

Arranged upon the opposite sides of the compartment 20 as well as the chamber 26 are drawer spaces to receive drawers 28 having suitable handles thereon and which may be in the form of knobs as shown.

The lower portion of the rear of the cabinet 15 is open, so access may be had to a drawer 29 that is carried by the frame 10, whereby it is raised and lowered with the platform, it being noted from Figure 3 that the drawer is slidably mounted upon strips 29' secured to the lower 20 end of the confronting faces of the sides of the frame, and this open portion also allows access to the shelf 23 as well as the space between the latter and the bottom 7. The open portion is closed by doors 30 having suitable handles 25 thereon.

Arranged upon opposite sides of the cabinet in convenient reach, are suitable boxes for switches 31 and outlets 32, there being a switch for the radio and each of the lamps, and of course 30 the outlets are for electric apparatus such as a coffee percolator, toaster, heating pads and the like.

In the rear of the cabinet I provide a plug-in receptacle 33 which is adapted to be in electrical connection with a suitable source of current to supply current to the respective electrical devices of the cabinet above described.

From the above description and disclosure of the drawing, it will be obvious that I have provided a cabinet that is primarily designed for use on either side of a bed or between twin beds, as either occupant of the latter can control the electrical equipment of the cabinet through the medium of the switches and the cabinet can be 40 easily moved on its casters to any place to suit the convenience of the user, without fear of tilting or tipping, and this is especially true when the platform is disposed over a bed, due to the particular structure of the base, and of course 45 the platform can be adjusted to various heights, with very little effort through the medium of the means shown for that purpose.

While the cabinet is designed for use at a bed

side, it is of course useful any place and for every purpose, where a cabinet of this type is desired, especially for patients at home or in a hospital.

The cabinet can be constructed of any suitable material and in any size and shape, and of course can be decorated in any manner desired.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. In a cabinet, a platform, a frame secured to the underside of the platform, said platform being adjustable vertically within the cabinet, means including the frame for retaining the platform in adjusted positions, and a drawer carried by the frame for movement with the platform.

2. In a cabinet, a platform including a body portion, a frame secured to the underside of the body portion to carry the platform and engageable with the walls of the cabinet for vertical adjustment therein, an extension hingedly secured to the platform, means receivable in certain of the walls of the cabinet and including a 30 hand lever to provide adjustment of the frame and its platform and to retain the same in adjusted positions, and a wheeled base for the cabinet and including a portion to underlie the platform to balance the latter to prevent the cabinet 35 from tilting.

3. In a cabinet, a platform, a body portion included in the platform, a frame secured to the underside of the body portion to carry the platform and engageable with the walls of the cabinet for vertical adjustment therein, an extension hingedly secured to the body portion, means 40 for holding the extension level with the body portion, means for providing adjustment of the frame and its platform and for retaining the 45 same in various adjusted positions, said means including a lever pivotally secured to the underside of the body portion, arms extending from the lever, the side walls of the cabinet having bores arranged therein to receive the arms and spring means engaging the lever and a side wall 50 for retaining the arms in the bores.

FRANK H. THOMPSON.
